FREDERICK NIBLOCK, OF SINGAPORE, STRAITS SETTLEMENTS

CONSTRUCTION OF SPRING BUFFERS.

1,411,977.

Specification of Letters Patent. Patented Apr. 4, 1922.

Application filed January 10, 1922. Serial No. 528,133.

To all whom it may concern:

Be it known that I, FREDERICK NIBLOCK, a subject of the King of Great Britain, and resident of Keppel Harbour, Singapore, 5 Straits Settlements, have invented an Improved Construction of Spring Buffers, of which the following is a specification.

The object of the present invention is to provide a type of spring buffer which shall 10 be better able to resist fracture of the spring when under load than the buffers now in general use comprising a cylindrical or helical spring of square or other section.

According to this invention, the spring 15 buffer comprises a spring of the conical type and means whereby the movement of each larger and weaker coil of the spring when under load is successively arrested before such coil reaches a condition of undue distortion. With this object a spring is used in the buffer, the winding of which is of the usual conical type, that is to say the spring is of some section wire the coils of which vary in diameter from one end to the other. 20 If desired also the coils may increase in pitch from one end of the spring to the other as well as vary in diameter and thus be a combination of the conical and volute types of spring. In a conical and volute 25 form of spring the larger diameter coils move most when under compression. This is taken advantage of in the present invention. The conical spring is formed upon a mandrel preferably of such shape that when 30 the spring wire is wound thereon the coils lie closely against each other, but, if desired, the mandrel may be so shaped that the coils of the spring are at some pitch apart. The spring after being formed on this 35 mandrel is then extended to the final pitch required, which will always be greater than that of the mandrel upon which it has been formed, and the spring is then tempered. Consequently the spring so formed when 40 pressed close would fit the mandrel or a similar sized and shaped element. A second support element is now made somewhat like the mandrel but with a pitch greater than that of the original mandrel, and is positioned in the larger diameter end of the 45 spring which latter and the support are housed in any usual type of buffer frame. The mandrel upon which the spring is primarily formed may be a stepped mandrel or 50 it may be truly conical, the support element

being similarly shaped, that is, either stepped or conical.

The invention is illustrated in the accompanying drawings in which Fig. 1, is an elevation of a buffer with the spring in section 60 and the support element in position, Fig. 2, being an elevation of a mandrel suitable for forming the spring shown in Fig. 1.

In carrying out the invention, a mandrel 1 is provided upon the spiral steps 3 on which 65 the spring wire 2 of some suitable section, such as the square form shown, is wound. With the form of mandrel shown in Fig. 2, the coils of the spring would lie closely one against the other, the pitch α of the steps being equal to the depth A of the wire section. After being formed on the mandrel, the spring is taken off and opened out to the desired pitch and is then positioned in any usual type of buffer frame comprising, say, 70 upper and lower yokes 4, 5, adapted to be drawn together to compress the spring by outer rods 6 and a central rod 7, each of the three rods having an eye 8 and a retaining nut 9. A support element 10 is inserted in 75 the buffer frame and inside the larger diameter end of the spring 2, this support being formed with spiral steps or shoulders after the manner of the mandrel 1 but with the longitudinal pitch b of its steps greater than 80 the corresponding pitch α of the mandrel but less than the pitch to which the spring coils have been opened. Consequently the 85 larger diameter or lower coils of the spring 2, when in the uncompressed position round 90 the support 10, will all be free of the steps 10 α of the support.

When the spring is under compression the largest diameter end coil 2 a of the spring 2 will, owing to its greater movement, first bed 95 and come to rest on the largest diameter step 10 a of the support 10, and such coil 2 a will come to rest in a distortion condition of its wire lying between its full extension or free condition and its closed up limit corresponding to the initial disposition of the coils when being wound close together on the mandrel. The lowest coil 2 a of the spring will therefore bed on the corresponding step or shoulder of the mandrel before fracture 105 of the spring wire in that coil is at all likely to occur. After the largest coil has bedded in the manner described, the resistance of the spring will now be met by the second largest coil which will offer greater resist- 110

ance than the previous coil now bedded but less than the succeeding free coils. This second coil will also ultimately bed on the support 10 and the resistance be then mainly taken up by the third coil and so on in sequence throughout the spring as successive coils become bedded on the support and pass out of action, the shock of compression being thus distributed over the various sections 10 of the springs, each section or coil being put out of action before reaching its elastic limit, instead of the weakest coil being liable to be unduly strained as in the usual conical type of spring.

15 The mandrel upon which the spring steel is wound when hot, may be made of, say, only half the pitch of the support which is inserted in the buffer, and this support may be a sheet metal stamping or other abutment against which the thrust of the spring is taken.

Though the mandrel 1 and support 2 have been particularly described as of spiral stepped or shouldered construction, the mandrel 25 may take the form of a conical element, the support which is afterwards inserted in the coil being also a conical element but less acute than the mandrel, the sequential bedding of successive coils taking place on the more obtuse conical support element in the same way as that described with reference to the stepped element.

I claim.

1. A spring buffer, comprising, a coiled 35 spring, a stepped support co-operating with

the spring coils, the pitch of the steps of the support being less than that of the coils in the spring when uncompressed.

2. A spring buffer comprising, a spring the coils of which are wound in conical formation, a stepped support against the steps of which the spring coils are adapted to bed, the pitch of the steps of the support being less than that of the coils in the spring when uncompressed. 45

3. A spring buffer, comprising, a spring the coils of which are wound in conical formation, a spirally stepped support co-operating with the larger coils of the spring so that such coils may bed thereon, as the spring is 50 compressed, the pitch of the steps of the support being less than that of the coils in the spring when uncompressed.

4. A spring buffer, comprising, a spring the coils of which are wound in conical formation, a buffer frame within which the spring is housed, a spirally stepped support element housed within the spring, the steps of the support being adapted to arrest the movement of the spring coils when the 60 spring is compressed, and the pitch of the steps of the support being less than that of the coils in the spring when uncompressed. 55

In testimony whereof I affix my signature in presence of two witnesses.

FREDERICK NIBLOCK.
